United States Patent

Des. 240,525
Patented July 13, 1976

240,525

PEN

Eugene Defores, Nantes, France, assignor to Waterman, S.A., Paris, France

Filed June 19, 1974, Ser. No. 480,694

Term of patent 14 years

Int. Cl. D19—06

U.S. Cl. D19—47

FIG. 1

FIG. 2

FIG. 3

FIG. 1 is a perspective view of a pen showing my new design;

FIG. 2 is an exploded front elevational view; and
FIG. 3 is an exploded left side elevational view.

The bottom of the pen is plain and unornamented.

I claim:

The ornamental design for a pen, substantially as shown and described.
